[57] **CLAIM**

The ornamental design for a combined rotary cassette and filmstrip holder, as shown and described.

DESCRIPTION

FIG. 1 is a perspective view of a combined rotary cassette and filmstrip holder showing my new design;

FIG. 2 is a rear elevational view thereof;

FIG. 3 is a cross-sectional view taken along any one of the lines 3—3 in FIG. 2;

FIG. 4 is a perspective view of an alternate embodiment of the combined rotary cassette and filmstrip holder;

FIG. 5 is a rear elevational view thereof; and

FIG. 6 is a cross-sectional view thereof taken along any one of the lines 6—6 in FIG. 5.

The bottom surfaces of both embodiments are planar and unornamented.

FIG. 1.

FIG. 2.

FIG. 4.

FIG. 5.
